Fig. 3.

Inventor,

Charles O. Guernsey
by his Attorneys,
Howson & Howson

UNITED STATES PATENT OFFICE

CHARLES O. GUERNSEY, OF PHILADELPHIA, PENNSYLVANIA

MUFFLER

Application filed December 31, 1926. Serial No. 158,260.

This invention relates to vehicles, and more particularly it relates to a muffler for discharging exhaust gases through the roof of a vehicle powered by an internal combustion engine.

The prime object of this invention is to provide a muffler which can be readily combined with the cooling system of an internal combustion engine used for propelling a railway car or other similar vehicle so that the air used for cooling the radiator of the engine may be discharged through the same opening in the roof of the vehicle as are the exhaust gases from the engine.

Another object is to provide means for cooling the exhaust gases from an internal combustion engine by combining such gases with the air used for cooling the radiator of the engine cooling system.

A further object of the invention is to provide a muffler which is simple in construction, reliable and efficient in operation, and which can readily be installed on the roofs of railway cars.

With these and other objects in view the invention consists in the combination of elements and arrangements of parts herein-after more fully described and claimed, reference being had to the accompanying drawings in which:—

Figure 1 is a plan of a muffler constructed according to the preferred embodiment of my invention,

Fig. 2 is a vertical transverse section of the muffler, showing the same installed on the roof of a railway car,

Fig. 3 is a detail section of the exhaust outlet passage.

The muffler comprises an annular ring 5, which is, as shown by Fig. 2, U-shaped in cross-section, and has an upstanding vertically disposed flange 6 and a depending flange 7 on its inner periphery, the diameter of the flange 6 being slightly greater than the diameter of the flange 7.

A cylindrical band 8 is mounted inside of the ring 5, the lower edge of the band being tightly fitted within the lower flange 7 and secured thereto by rivets or other suitable

means. The upper edge of the band is bolted to the lower portion of the flange 6.

The disposition of the band 8 inside of the ring 5 is such that the upper edge of the band lies at a distance below the upper edge of the flange 6, while the exterior of the band is spaced slightly from the flange 6. This provides a circumferential slot 9 that serves as a continuous outlet passage on the inner side of the muffler (see Fig. 3).

The ring 5 has fastened thereto a lateral branch 10, to which the exhaust pipe (not shown) from the engine is connected. The purpose of the branch is to provide an inlet which will be substantially tangent to the muffler body.

The muffler is mounted in an opening 11 with which the roof C of the car is provided. The opening has a diameter substantially equal to the diameter of the ring 5 and the muffler is inserted in this opening.

The exterior of the ring 5 has riveted thereto the vertical flange of an annular angle iron 12, the horizontal flange of which angle iron being fastened to the roof C by means of bolts 13, as shown by Fig. 2.

In this way the muffler will be rigidly mounted with only a portion thereof extending above the roof. The arrangement of the parts is such that the exterior of the car roof is not marred to any great extent.

The fan 14 indicated by broken lines in the drawings, may be centrally disposed within the muffler, independent thereof.

The purpose of the fan is to draw air upwardly through the muffler from the cooling system of the engine (not shown).

In the operation, the exhaust gases from the internal combustion engine will enter the muffler through the inlet provided by the branch pipe 10 and travel around the annular chamber provided by the U-shaped ring 5 and the band 8. The direction of the gases which whirl around the interior of the muffler, is indicated by the dotted arrows, Fig. 1. The gases after whirling around pass upwardly through the outlet provided by the annular slot 9, in the manner indicated by the arrows, Fig. 2 and Fig. 3.

When the fan 14, is delivering the air from

the radiator, it creates an up-draft, and since the exhaust gases are discharged around the air opening, these gases will be carried above the car. In this manner any possibility of the exhaust gases entering the car will be avoided. Furthermore, the large volume of air passing through the central opening in the muffler from the fan will have a beneficial effect in cooling the exhaust gases. On the other hand, should the use of a fan in the central opening of the muffler not be possible for any reason, the discharge of the exhaust gases through the slot 9 will also cause an up-draft through the central opening, and in this way air will be drawn therethrough.

It is to be understood that while I have, in the present case, described one form of the invention, I am not limited to the precise structure disclosed, and that other forms of mufflers may be utilized without departing from the scope of the appended claims.

The shape of the cross-section of the circumferential exhaust opening may be modified so as to vary the amount of air drawn up through the central opening.

The gases rotating continually around the ring gives a more even discharge than is possible with a muffler having a closed end. The rotation of the gases will tend to set up a partial vacuum in the exhaust pipe between explosions and the design may be modified to accomplish this object of the invention.

I claim:

1. Means for discharging the exhaust gases from an internal combustion engine including a U-shaped ring provided with an inlet on its exterior and having upper and lower vertically disposed flanges, the diameter of the lower flange being less than the diameter of the upper flange, a cylindrical band mounted inside of the said ring and secured to said flanges to produce an unobstructed annular chamber, the exterior of the band being spaced from the upper flange so as to provide a substantially unobstructed circumferential outlet for the chamber, and a rotary fan disposed centrally within the said ring and adapted to create an up-draft therethrough, said inlet being substantially tangential to said cylindrical band.

2. A muffler comprising an unobstructed annular chamber having a flat cylindrical inner wall and provided at one side thereof at the inner face of said wall with a substantially unobstructed annular outlet, a fan for creating a draft axially of the annular chamber and disposed within the circular space defined by the annular chamber and means for admitting exhaust gases to said chamber in a direction substantially tangential to said inner wall.

CHARLES O. GUERNSEY.
